UNITED STATES PATENT OFFICE

157,374

ELECTRICAL CONTROL UNIT

George C. Izenour, New Haven, Conn.

Application September 24, 1949, Serial No. 5,154

Term of patent 14 years

(Cl. D26—13)

To all whom it may concern:

Be it known that I, George C. Izenour, a citizen of the United States of America, residing at New Haven, in the county of New Haven and State of Connecticut, have invented a new, original, and ornamental Design for an Electrical Control Unit, of which the following is a specification, reference being had to the accompanying drawings, forming a part thereof, in which:

Fig. 1 is a plan view of an electrical control unit, showing my new design, associated control units of like design being included in dotted lines for illustrative purposes only.

Fig. 2 is a front elevation thereof; and

Fig. 3 is a perspective view.

What I claim is:

The ornamental design for an electrical control unit, substantially as shown and described.

GEORGE C. IZENOUR.
